UNITED STATES PATENT OFFICE.

BARTLETT N. TORREY, OF CRESTON, IOWA.

THILL-COUPING CLAMP.

SPECIFICATION forming part of Letters Patent No. 241,251, dated May 10, 1881.

Application filed November 29, 1880. (No model.)

To all whom it may concern:

Be it known that I, BARTLETT N. TORREY, of the United States, residing at Creston, in the county of Union and State of Iowa, have invented certain new and useful Improvements in Thill and Tongue Coupling Clamps; and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification, in which—

15 Figure 1 is a perspective showing my improved clamp. Fig. 2 is a vertical sectional elevation, showing my improvement applied in coupling a thill to an axle. Fig. 3 is a sectional elevation, showing its application in 20 coupling a tongue or draft-pole.

This invention relates to a thill and tongue coupling clamp, or clamp for compressing elastic anti-rattler blocks in thill and tongue couplings; and the invention consists in constructions and combinations of parts hereinafter described, and set forth in the claims hereto annexed.

Referring to the drawings by letters, the same letter indicating the same part in the different figures, letter A represents a section of a carriage-axle; B, a clip; C, jaws projecting from the clip; D, rear end of a thill; E, thill-iron with eye e on its end, and F rubber-block placed between the eye e and clip B. The thill-iron E is curved upward and forward from the eye e. The foregoing parts are shown by full lines and constitute parts of an ordinary vehicle, which may be constructed in any usual manner.

40 G represents my improved clamp, having jaws gg on one end, which are preferably curved so that they may clasp pretty closely around the rear end of the thill D or iron E. The jaws g are journaled to each other at g', and have 45 their rear ends extended to form jaws g''. Separating the jaws g will cause the jaws g'' to approach each other, and vice versa.

H H are jaws projecting laterally, one from each jaw g, and are located near the pivoted 50 end of the jaws g, and preferably curved inwardly or toward each other at their outer ends.

I also prefer to have them curved or inclined toward the jaws g'' at their outer ends.

At Fig. 3 an ordinary tongue or draft pole iron J, with coupling-eye j, is shown, which projects straight or nearly straight from the axle, and does not curve upwardly as does the thill-iron E.

K is a lever, tapering or wedge-shaped at one end.

When used in coupling thills, as shown at Fig. 2, the clamp is placed over the axle A, with the jaws g embracing the thill D, or the iron E, or both, according to the extension of the thill-iron beyond the end of the thill. The 65 wedge-shaped end of the lever K is then passed downward between the jaws g'', and, forcing them apart, will force the jaws g toward each other, so as to hold the thill securely. The lower end of the lever rests against the axle, and its 70 upper end may be drawn backward to draw the eye e against the elastic block F, and compress it so that the ordinary coupling-bolt may be inserted. The jaws g may be adjusted on the thill, and a lever used without a wedge-shaped end, if preferred. A piece of leather 75 or other soft material may be attached to the lever where it rests against the axle, or simply placed between said parts.

When used in coupling tongues or draft-poles 80 without raising the forward end of the tongue, the clamp is placed on the axle with its jaws H pointing downward, so that they may embrace the coupling-iron J. The lever K may then be used in the same manner as hereinbefore described, to force the iron J backward and compress the rubber so that coupling may be effected. By means of the jaws H the clamp is made to draw the tongue-iron J backward 85 and not upward.

I do not limit my claims to the exact construction of the clamp as shown; but

What I claim as new, and desire to secure by Letters Patent, is—

1. A coupling-clamp having hinged jaws 95 adapted to embrace the thill or tongue, with their rear ends extended to form other jaws which receive and hold a lever, by which force may be applied to compress the elastic block between the thill or tongue iron and axle, substantially as shown and described.

2. A coupling-clamp having hinged jaws g

- or H, adapted to embrace the thill or tongue, with their rear ends extended to form other jaws, $g'' g''$, in combination with a wedge-shaped lever, which may be used to tighten the hold of the jaws g or H on the thill or tongue, while at the same time used to force the thill or tongue backward and compress the elastic coupling-block, substantially as and for the purpose specified.
- 10 3. A coupling-clamp having jaws $g g$, with other jaws, H H, projecting laterally therefrom, and with their rear ends extended to form other jaws, $g'' g''$, by means of which both sets of first-named jaws may be operated, substantially as and for the purpose specified.
- 15 4. In combination with a coupling-clamp hav-

ing hinged jaws $g H g''$, a lever which may be inserted between the jaws g'' and used to compress the elastic rubber in thill or tongue couplings, substantially as and for the purpose specified. 20

5. In combination with a coupling-clamp having hinged jaws $g H g''$, a wedge-shaped lever, K, adapted to force the jaws g'' apart, substantially as and for the purpose specified. 25

In testimony whereof I affix my signature in presence of two witnesses.

BARTLETT N. TORREY.
